UNITED STATES PATENT OFFICE.

CHARLES LAVIER, OF SYRACUSE, NEW YORK.

GARMENT-PRESSING MACHINE.

Application filed August 22, 1922. Serial No. 583,620.

To all whom it may concern:

Be it known that I, CHARLES LAVIER, a citizen of the United States, residing at Syracuse, in the county of Onondaga and State of New York, have invented certain new and useful Improvements in Garment-Pressing Machines, of which the following is a specification.

This invention relates to improvements in clothes pressing machines, and has for its object to provide novel, simple and powerful means for effecting the pressing strokes of a movable buck towards a stationary presser head. A further object is to provide a pressing unit comprising an upright hydraulic cylinder, having a concentric chamber in which is disposed a plunger that supports and operates the movable buck, the said plunger being raised by the displacement of the fluid contained in said cylinder, and the said buck and said plunger being lowered after each pressing operation by gravity. And a further object is to provide novel means for regulating the speed at which the buck and plunger may be raised and lowered, as well as for varying the degree of the working pressure of the machine.

I attain these objects by the means set forth in the detailed description which follows, and as illustrated by the accompanying drawings, in which—

Figure 1 is a central vertical section, taken on line 1—1 of Fig. 2. Fig. 2 is a horizontal section, taken on line 2—2 of Fig. 1. And Fig. 3 is a transverse vertical section, taken on line 3—3 of Fig. 1.

In the drawing, 2 represents an upright cylinder, which is shown mounted on a flaring base 2', the latter extending below an imperforate bottom 2^a. Concentrically within the main body 2 is formed a smaller upright cylinder 2^b, which extends from the bottom 2^a to the top 2^c, the top end of the cylinder 2^b being open. The top 2^c is shown integral with the body 2, but it may comprise a separate part, in a well-known manner. The arrangement of the cylinders 2 and 2^b is such that a clear annular water or fluid chamber 2^d surrounds the hoisting cylinder 2^b, and these two chambers are connected for the passage of fluid, by means of a by-pass, which comprises a duct 2^e, a pipe 3, a valve 4, of the plunger type operable in a cylinder 4', which is tapped by the pipe 3, and by an extension 3' of the said pipe, the latter connecting by means of

a port 2^f with the chamber 2^d. The plunger 4 has a stem 4^a, which is operatively connected to a lever 5, one end of said lever being pivoted to a link 5', which in turn is pivotally supported by the casing 4', while the other end of the said lever is pivoted to a rod 6, which is operable vertically by means of a pedal 6' (see full and dotted lines in Fig. 1). The fluid α contained in the chamber 2^d can only pass into the chamber 2^b through the by-pass and valve 4, and the said valve is arranged to entirely shut off, as well as to regulate the flow of the fluid between said chambers, that is to say, for accelerating or retarding the said flow.

7 represents a reciprocatable plunger or pedestal which operatively fits the bore of the cylinder 2^b, and is raised and lowered by the alternate displacement of the fluid in the chambers 2^d—2^b, and for this purpose the lower end of the plunger 7 is normally spaced from the bottom 2^a, as shown in Figs. 1 and 3. At the top of the cylinder 2 is arranged a stuffing-box comprising an integral annular part 2^x, a ring 8, and a circular packing 8', the said parts being adjustably held in place by bolts 8^a. Above the body 2 the plunger passes loosely through a horizontal table 9, and upon its top end is rigidly mounted the lowermost clothes-pressing member 10, which is usually called the buck, the latter being movable vertically with the plunger for effecting the pressing, as well as the release strokes of the machine. 12 represents the presser-head, which generally corresponds to the buck 10 in size and shape. The head 12 is preferably stationary and is supported some distance above the idle position of the buck (see Fig. 1), by means of a bracket 13, to the goose-neck top end 13' of which the head is rigidly secured. The lower end of the bracket 13 is preferably rigidly secured to the rear face of the body 2, as best seen in Fig. 3. The buck 10, as well as the head 12, may follow any of the usual constructions, and both of these parts may be charged with steam or other hot vapor for properly heating the same, by means of pipes 10' and 12', which tap the backs of the buck and head.

The fluid α , which is usually water, or may be oil, preferably nearly fills the annular chamber 2^d, as best seen in Fig. 1, and this level of the liquid α should be maintained as nearly constant as possible, for

effecting the proper working of the press. To regulate this level of the liquid, I provide a float-controlled valve 14, which is disposed in a small compartment 15, that communicates with the chamber 2^a, the said compartment being tapped by a waste or overflow pipe 15'. The valve 14 and its float 14' are so arranged that whenever the level of the liquid α rises above that shown in Fig. 1, the float is lifted and the valve is unseated, thereby allowing the surplus water to escape or waste through the pipe 15'.

As explained, the raising and lowering of the plunger 7 and the buck 10 is effected by the displacement of the fluid α . To accomplish this, the relatively narrow empty space at the top of the cylinder 2 is charged with either compressed air or steam pressure. This operating pressure is admitted to the chamber 2^a through a pipe 16, in which is connected, a valve 17, the latter having a handle 17', which when depressed, as from the full to the dotted position shown in Fig. 1, opens the valve 17. The charging of the void in the cylinder 2 with this pressure forces the liquid α from chamber 2^a into the bottom of chamber 2^b, and drives the plunger 7 and buck 10 upwardly against the head 12, as shown by dotted lines in Fig. 1, and by the full lines in Fig. 3, for effecting the pressing of garments which may be supported by the buck. This action of the fluid pressure will be best understood by comparing Fig. 1 with Fig. 3. If the valve 4 is wide open, when the air or steam is turned on, the plunger and buck will move upwardly rapidly, since the by-pass has a relatively large capacity. So also, at the end of the pressing operation, after the air valve 40 has been opened for exhausting the pressure, the plunger and buck will descend more or less rapidly owing to the weight of said parts, and the ease by which they displace the fluid α . The plunger 7 and the buck 10 may be raised and lowered at any speed less than maximum by the operation of the valve 4, which controls the by-pass. Furthermore, the pressure upon the garments may be mained even though the air pressure has been released, by closing the valve 4 in advance of the opening of the valve 17, for preventing the fluid α from being forced back into the chamber 2^a.

The plunger 7 requires lubrication, and this is supplied by an oil-cup 18, which feeds the lubricant by gravity through a duct 18' in the top 2^c, and thence around the plunger via a circular duct 18^a. The reciprocatable movements of the plunger carry the lubricant upwardly to the packing 8', as well as downwardly from the duct 18^a.

My clothes pressing machine is extremely simple. By mounting the buck upon the vertically movable pedestal 7, to which the pressing power is directly applied, enables

me to carry out the pressing operations without appreciable loss of power, and by providing the stationary presser-head 12, and mounting said head upon the bracket which is supported by the main hydraulic cylinder, greatly simplifies, as well as cheapens the construction, assembling and operation of the machine. The foregoing novel features, when taken with the novel provision of the speed-controlling valve which is located in the by-pass, enables me to produce a machine that is more powerful, more economical, and contains less operating parts, than any other device of the class known to me.

Having thus described my invention, what I claim, is—

1. The combination with a stationary presser-head and a movable pressing buck, of a hydraulic cylinder disposed beneath and supporting said pressing parts, said cylinder being partially filled with fluid and having a concentric chamber in the line of the vertical axis of said pressing parts, a pedestal directly supporting said buck and being reciprocatable in said chamber, and means for admitting fluid pressure into said cylinder for effecting the raising of said pedestal and said buck.

2. A clothes pressing machine comprising a hydraulic cylinder adapted to be partially filled with liquid and having an inner concentric chamber communicating with the cylinder by means of a by-pass, a valve in said by-pass adapted to regulate the flow of the liquid between the cylinder and the chamber, a stationary presser-head supported by the cylinder above said chamber, a plunger reciprocatable in said chamber by the displacement of said liquid, and a pressing buck mounted on said plunger between the cylinder and said head and being movable relatively to said head.

3. In a clothes pressing machine, a hydraulic cylinder adapted to be partially filled with fluid, a plunger reciprocatable in an inner concentric chamber which communicates with said cylinder by means of a by-pass, means for admitting fluid pressure for forcing said fluid from said cylinder into said chamber for raising said plunger, a pressing buck mounted upon and movable with said plunger, a stationary presser head supported by said cylinder in spaced relation to and in the path of the vertical movement of said buck, and means for stopping and for varying the speed of the reciprocatable movements of the plunger and buck.

4. A clothes pressing machine including a hydraulic cylinder adapted to be partially filled with liquid, and having a vertically arranged concentric chamber connected with the cylinder by a by-pass, a stationary presser head supported by said cylinder above said chamber, a pressing buck dis-

posed between said head and said cylinder and movable towards and away from said head, a pedestal reciprocatable in said chamber by the alternate displacement of the said liquid, said pedestal supporting and operating said buck, and means for forcing said liquid from the cylinder into said chamber for raising said pedestal and said buck, the said liquid adapted to be forced back into the cylinder by the downward movement of said pedestal.

In testimony whereof I affix my signature.

CHAS. LAVIER.
